UNITED STATES PATENT OFFICE

FREDRICH J. RODE, OF CHICAGO, ILLINOIS, ASSIGNOR TO MARQUETTE TOOL & MFG. COMPANY, OF CHICAGO, ILLINOIS, A CORPORATION OF ILLINOIS

CUSHIONING DEVICE FOR SHEET-METAL PRESSES

Application filed May 25, 1929. Serial No. 365,962.

This invention relates in general to cushioning devices, but more specifically to pneumatic cushions for presses of the type in which the metal is shaped by means of co-operating dies, one of which is reciprocable toward and away from the other, the work being clamped or held by means of a blank or work holding element which co-operates with the reciprocable die member, the blank or work holder being resisted in its movement in one direction by a pressure pad, the latter being resisted by the fluid pressure in the cushion, and one of the objects of the invention is to provide in a pneumatic cushion of this character improved means for controlling the return of the pressure pad whereby the latter may be prevented from directly returning with the ram of the press or the co-operating die, when the latter starts to move away from the work.

20 A further object is to provide improved means for controlling the return of the pressure pad.

To the attainment of these ends and the accomplishment of other new and useful objects as will appear, the invention consists in the features of novelty in substantially the construction, combination and arrangement of the several parts hereinafter more fully described and claimed and shown in the accompanying drawings illustrating this invention, and in which

Figure 1 is a view partly in elevation, partly in section, partly broken away and with parts omitted, of a sheet metal press having a cushion and control mechanism constructed in accordance with the principles of this invention, applied thereto.

Figure 2 is an enlarged detail vertical sectional view of the cushion proper.

Figure 3 is a view on an enlarged scale taken on line 3—3, Figure 1.

Figure 4 is a view taken on line 4—4, Figure 3.

Figure 5 is a detail sectional view taken on line 5—5, Figure 4.

This invention is adapted for use with either what is known as a single acting or a double acting press and in either application of the invention, suffice it to say the press is

provided with a reciprocating ram 10 movable on upright guides 11, a crank shaft 12 being provided for reciprocating the ram and carried by the ram is a die member 13 which co-operates with a die member 14 mounted upon a bed plate 15 supported by the bed 16 55 of the press.

Carried also by the ram 10 and movable with and with respect to the ram in any well known manner is a die member 17 which co-operates with a die member 18, the latter being supported preferably by means of pins 19 that pass loosely through the bed plate 15 and engage and rest upon a pressure pad 20, the latter operating in an opening 21 in the bed 16 of the press. 60

Arranged beneath the press bed and spaced a suitable distance therebelow is a support 22 which is held in position in any suitable manner and mounted upon this support are a plurality of cushion elements, any number of which may be provided, and as the construction and operation of each of the cushion elements is the same the specific description of one will apply to them all. 70

Each of the cushion elements embodies superposed cylinder elements 23—24 separated from each other by means of a partition 25 forming one of the heads of the cylinders. 75

Reciprocable in the respective cylinders are pistons 26—27 connected by means of a piston rod 28 that passes through a suitable stuffing box 29 in the head 25. The piston rod 28 is provided with a passage 30 opening through the end thereof forming communication with one of the cylinders and also opening laterally through the piston rod 28 as at 31 so as to form communication between the superposed cylinders 23—24 85 beneath the respective pistons 26—27. 90

A piston rod 32 is also connected with the pistons and the rod 28 and passes through a suitable stuffing box 33 in the head 34 of the uppermost cylinder and these piston rods 32 are connected by suitable couplings 35 with the pressure pad 20. 95

Communicating with each of the lower cylinders 23 are pipes 36 which have communi- 100

cation with each other through a connecting pipe 37.

The pipe 37 is connected by means of a suitable connection 38 with a supply pipe 39, which in turn is connected by means of a branch pipe 39^a, leading from a tank or container 40, the latter receiving a supply of fluid under pressure by means of a suitable supply pipe 41 leading from a suitable source.

The air or fluid passing through the pipe 39 will be delivered into the lowermost cylinder 23 of the cushion and a portion of the air will flow through the passage 30 out of the opening 31 into the cylinder 24 beneath the piston 27 to form a resistance pressure to the pressure pad 20 when the latter is lowered to cause the pistons 27-26 to be lowered in the cylinders and thereby yieldingly resisted in their downward movement by the pressure of the fluid in the cylinders 23.

The cylinders 23-24 are respectively provided with inlet openings 42-43 which may be connected by means of a pipe 44 which in turn is connected by means of a pipe 45 with a supply pipe 46, so that at a predetermined time in the cycle of operation of the press fluid under pressure will be admitted into the cylinders 23-24 above the pistons 26 and 27 to neutralize or overcome the pressure of the fluid beneath the pistons 27 and thereby retain or hold the pistons 26-27 at the limit of their lowermost movements to prevent the pressure pad 20 from directly following the ram 10 when the latter starts to ascend.

All of the above referred to parts are of the ordinary and well known construction but are specifically described herein in order that a full understanding of the present invention as applied to such a type of cushion, will be had.

If desired, the respective cylinders of the cushions may be connected in the manner shown, that is in groups so as to increase the efficiency of the device and thereby obviate the necessity of superposing a number of cylinders.

As shown more clearly in Figure 2 of the drawings, one set of cylinders or cushions have communication with the pipe 46 through which fluid is supplied to and permitted to escape from the upper side of the respective pistons 26-27. Another set or series of the cylinders have communication on the upper side of the respective pistons 26-27 with a pipe 47 which in turn has communication with a pipe 48 and through the medium of a pipe 49 has communication with a pipe 50, through which latter air or fluid may be supplied to the respective cylinders on the top sides of the pistons and allowed to escape therefrom.

In order therefore to control the operation

of the cushioning device in so far as the return of the pressure pad 20 and the respective pistons 26-27 is concerned, it is only necessary to control the flow of the fluid through the pipes 46-50 and this may be so regulated or controlled as to permit air (preferably from the atmosphere) to enter the cylinders on the top sides of the pistons to prevent the formation of a vacuum or partial vacuum on the top sides of the cylinders and subsequently to permit fluid under pressure to enter the cylinders on the top sides of the pistons to overcome the fluid pressure under the pistons and thereby retain the pistons in their lowermost positions, after which the fluid pressure on the top sides of the pistons is released and allowed to escape (preferably to the atmosphere) so that the pressure on the bottom sides of the pistons will return the pistons and consequently the pressure pad 20 to their normal positions.

To that end there is provided a valve casing 51 which is provided with a series of openings 52-53-54 and 55. To the opening 53 is connected one end of the pipe 39 and to the opening 52 is connected the extremity 39^a of the pipe 39^a.

To the opening 54 is connected one end of the pipe 50 while to the opening 55 is connected one end of the pipe 46, as shown more clearly in Figure 5 of the drawings.

Arranged within the valve casing 51 is a passage 56 formed by partitions and the walls of the passage are provided with openings 57-58 therethrough controlled respectively by means of valves 59-60.

Two sets of these valves, each comprising one of the valves 59 and one of the valves 60, are provided for the following purpose. One set of the valves 59-60 controls the supply of the fluid and the exhaust of such fluid from the top sides of the pistons in one group of the cylinders and the other set of the valves 59-60 controls the supply of fluid to and the exhaust of the fluid from the top sides of the pistons in the other group of cushion cylinders, and as the operation of each set of the valves is the same the specific description of one set will apply to both.

Referring more particularly to Figure 3, the valves 59-60 therein illustrated control the supply of fluid to the top sides of one set of the pistons for holding the pistons down at the limit of their lowermost stroke and this set of valves is arranged to operate with respect to the other set of valves which controls the fluid to the other set of the pistons, and vice versa, so that the operation of one set will not interfere with the other.

The valves shown in Figure 3 are in the position they will assume when the ram is at the limit of its uppermost movement so as to establish communication between the cylinders on the top sides of the piston and

the atmosphere to permit the fluid on the top sides of the piston to escape, the pistons having reached their uppermost position by reason of the fluid pressure beneath the pistons and the pressure pad 20 will be at the limit of its uppermost position or as shown in Figure 1, that is so that the air on the top sides of the pistons will escape to the atmosphere through an exhaust pipe 61 leading from the valve casing 51, as the valve 60 will be open permitting the air to flow through the pipe 60 into the valve casing 51 through the passage 58 and out of the exhaust pipe 61. The valve 59 controlling the supply of fluid to the top sides of the pistons from the tank or container 40 being closed.

When the valve 59 is opened the valve 60 will be closed and this will open the passage 57 in the valve casing 51 so as to permit the fluid under pressure to flow from the container 40 through the supply pipe 39^a through the end or branch 39^b of the pipe 39^a into the valve casing through the passage 57, into the passage 56 and from the passage 56 into the pipe 46 and thence to the cylinders on the top sides of the pistons.

This will occur at the time just before the pistons 26—27 reach the limit of their lowermost movement.

Obviously the valves controlling the communication between the pipe 39 and pipe 50 which supplies the fluid pressure to the top sides of the pistons in the other groups of cylinders of the press will operate in unison with the valves just described so that an equal or uniform pressure will be supplied to all of the cushions on the top sides of the pistons at the same time.

The fluid pressure from the top sides of the pistons will be exhausted from all of the cylinders at the same time by the simultaneous operation of the respective controlling valves.

Any suitable means may be provided for operating the valves 59—60, but preferably as follows.

Each of the valves 59—60 is provided with a spring 62 for controlling them and which springs operate upon the respective valve stems 63—64.

A rocker member 65 is provided for operating each pair of valves 59—60. This member 65 is preferably pivotally supported intermediate its ends as at 66 and is provided preferably with portions 67 adapted to engage the ends of the respective stems 63—64.

Anti-friction rollers 68—69 may be provided on the member 65 and these rollers 68—69 are laterally offset with respect to each other so as to be respectively engaged by cams 70—71 by the rotation of a supporting member 72 to which the cams are connected. These cams 70—71 are also laterally offset with respect to each other and are positioned at any desired angle with respect to each

other about the member 72 so that when the member 72 is rotated in the direction indicated by the arrow in Figure 3 and with the valves in the position as shown in said figure, the cam 70 will engage the anti-friction roller 68 to rock the member 65 so as to open the valve 59 against the stress of its spring and permit the valve 60 to close under the stress of its spring.

This will position the anti-friction roller 69 so as to be engaged by the cam 71 on the member 72 when the latter is further rotated and when the anti-friction roller 69 is engaged by its cam the member 65 will be again rocked to the position shown in Figure 3, to open the valve 60 and permit the valve 59 to be closed.

Thus it will be seen that the valves 59—60 will be alternately opened and closed at predetermined times in the cycle of operation of the press according to the position of the cams 70—71 on the member 72. To change the time in the cycle of operation at which the valves operate, it is only necessary to re-position the cams 70 and 71 upon the supporting member 72.

Obviously, one of these rocker members 65 and one of the operating members 72 with its respective cams 70 and 71 is provided for each set of valves 59—60.

The operating valve mechanism and the valve casings may be mounted upon a suitable support 73 which in turn may be mounted upon a bracket 74.

The rocker member 65 may be provided with an arm 75 to which an anti-friction roller 76 is connected. A spring pressed abutment 77 may be provided adjacent the path of movement of the roller 76 and this abutment 77 may be provided with a conical shaped extremity 78 so as not to interfere with the operation of the roller 76.

The spring pressed abutment or member 77 is provided for a double function, to-wit: the conical extremity 78 thereof under the influence of the spring 79 will assist in shifting the member 65. That is, after the movement of the member 65 has been started by the cam, the spring 79 forcing the abutment 77 and the conical face 78 against the roller 76 will continue the movement of the member 65.

After the member 65 has assumed the limit of its movement the spring pressed abutment 77 will also serve the purpose of holding the member 65 against further rocking movement until engaged by one of the cams 70—71.

Any suitable means may be provided for rotating the member 72 but a simple and efficient means embodies a sprocket chain 80 which passes over a suitable sprocket wheel connected with the member 72 and also over a suitable sprocket wheel 81, which latter is connected with any rotatable part of the press, preferably the crank shaft 12.

5 The cams 70 and 71 may be secured to the member 72 for adjustment with respect thereto in any suitable manner preferably by means of a fastening bolt 82 which passes through a suitable slot 83 in the member 72 and is anchored in any suitable manner. The member 72 may be provided with flanges 84 between which the base 85 of the cam member 70 are adapted to be positioned.

10 It is thought that the operation of this mechanism will be clearly understood from the foregoing description, but briefly stated it is as follows. When the ram is in its uppermost position the respective valve 59—60 15 will be positioned as shown in Figure 3 so that any air or fluid which may have been supplied to the cylinders on the top sides of the pistons from the supply tank 40 will be exhausted by forming communication between the cylinders on the top sides of the pistons and the atmosphere through the pipe 61.

20 The fluid pressure on the bottom sides of the pistons will then hold the pressure pad 25 20 in its uppermost position.

As the pressure pad 20 descends the fluid on the bottom sides of the pistons will be compressed and air will be sucked into the cylinders on the top sides of the pistons 30 through the exhaust pipe 61 and through the respective pipes 46—50. This operation will continue until the pistons have about reached the limit of their lowermost movement at which time the cam 70 will engage 35 the anti-friction roller 69 and rock the member 65 to close the valve 60 and open the valve 59. This will establish communication between the tank or reservoir 40 in the manner described to the top sides of the pistons, 40 thereby causing the fluid pressure on the bottom sides of the pistons to be neutralized or overcome, with the result that the pistons will be locked or held at the limit of their lowermost movement and will be locked 45 against return until the other cam 71 rocks the member 65 in the opposite direction to close the valve 59 and open the valve 60, thereby permitting the fluid pressure on the top sides of the pistons to exhaust to atmosphere so that the pistons and the pressure pad can be returned by the pressure on the bottom sides of the pistons.

50 While the preferred form of the invention has been herein shown and described, it is to be understood that various changes may be made in the details of construction and in the combination and arrangement of the several parts, within the scope of the claims, without departing from the spirit of this 55 invention.

60 What is claimed as new is:—

1. A cushioning device for presses, said cushioning device embodying a piston and cylinder element relatively movable, means 65 for supplying fluid under pressure to one

side of the piston to yieldingly resist such relative movement in one direction, means for supplying said fluid pressure to the other side of the piston to restrain relative movement of said cylinder and piston, valve mechanism for controlling the direction of flow of said fluid, and means for exhausting the fluid from one side of the piston. 70

2. A cushioning device for presses, said cushioning device embodying a piston and cylinder element relatively movable, means for supplying fluid under pressure to one side of the piston to yieldingly resist such relative movement in one direction, means for supplying said fluid pressure to the other side of the piston to restrain relative movement of said cylinder and piston, valve mechanism for controlling the direction of flow of said fluid, and means automatically operating at a predetermined time in the 80 cycle of operation of the press for exhausting the fluid from one side of the piston. 85

3. A cushioning device for presses, said cushioning device embodying a piston and cylinder element relatively movable, means for supplying fluid under pressure to one side of the piston to yieldingly resist such relative movement in one direction, means for supplying said fluid pressure to the other side of the piston to restrain relative movement of said cylinder and piston, valve mechanism for controlling the direction of flow of said fluid, and means responsive in its operation to a movable part of the press for exhausting the fluid from one side of the 90 piston. 95

4. A cushioning device for presses, said cushioning device embodying a cylinder and piston relatively movable, a supply pipe for supplying fluid under pressure to one side of said piston, means connecting said supply pipe with the other side of the piston to supply said fluid pressure thereto to restrain such relative movement, an exhaust outlet, and means for connecting the said other side of the piston with said outlet to exhaust the fluid from said other side of the piston, while the fluid pressure on the first recited side of the piston remains active to produce said relative movement of the cylinder and piston elements. 105

5. A cushioning device for presses, said cushioning device embodying a cylinder and piston relatively movable, a supply pipe for supplying fluid under pressure to one side of said piston, means connecting said supply pipe with the other side of the piston to supply said fluid pressure thereto to restrain such relative movement, an exhaust outlet, and means automatically operable at a predetermined time in the operation of the press for connecting the said other side of the piston with said outlet to exhaust the fluid from said other side of the piston, while the fluid pressure on the first recited side of the piston 110

- remains active to produce said relative movement of the cylinder and piston elements.
6. A cushioning device for presses, said cushioning device embodying a cylinder and piston relatively movable, a pipe for supplying fluid under pressure to one side of the piston to yieldingly resist such relative movement, a source of fluid supply with which said pipe is connected, a pipe leading to the other side of the piston, an exhaust, and means operating automatically to connect the second recited pipe with said source of supply to restrain such relative movement of the cylinder and piston elements, the said means also operable automatically to connect the last said pipe to said exhaust to exhaust the fluid from the said other side of the piston.
7. A cushioning device for presses, said cushioning device embodying a cylinder and piston relatively movable, a pipe for supplying fluid under pressure to one side of the piston to yieldingly resist such relative movement, a source of fluid supply with which said pipe is connected, a pipe leading to the other side of the piston, an exhaust, a valve device for connecting the second recited pipe with said source of supply, to restrain such relative movement of the cylinder and piston elements, a valve device for connecting the second recited pipe with said exhaust to exhaust the fluid from said other side of the piston, and means operating automatically to alternately open and close said valves in timed relation to each other.
8. A cushioning device for presses, said cushioning device embodying a cylinder and piston relatively movable, a supply passage for supplying fluid under pressure to one side of said piston to yieldingly resist such relative movement, a source of supply of fluid to which said passage is connected, a passage leading to the opposite side of the piston, an exhaust, a valve operable to connect the second said passage with said source of supply to prevent such relative movement and to disconnect the same from said source of supply, a valve operable to connect the second said passage with and disconnect the same from said exhaust, and means responsive in its operation to a movable part of the press for actuating said valve in timed relation with respect to each other.
9. A cushioning device for presses, said cushioning device embodying a cylinder and piston relatively movable, a supply passage for supplying fluid under pressure to one side of said piston to yieldingly resist such relative movement, a source of supply of fluid to which said passage is connected, a passage leading to the opposite side of the piston, an exhaust, a valve operable to connect the second said passage with said source of supply to prevent such relative movement and to disconnect the same from said source of supply, a valve operable to connect the second

- said passage with and disconnect the same from said exhaust, a rotatable member having spaced operative portions adapted to alternately actuate said valves in timed relation with respect to each other, and means for actuating said rotatable member.
10. A cushioning device for presses, said cushioning device embodying a relatively movable cylinder and piston, a source of supply of fluid under pressure for yieldingly resisting such relative movement, a passage leading to the other side of the piston, an exhaust, a spring controlled valve device for connecting said source of supply with said passage to maintain said cylinder and piston against such relative movement, a spring controlled valve device for connecting said passage with said exhaust, a rocker member for alternately actuating said valves, and means operating automatically at predetermined times in the cycle of operation of the press for rocking said rocker member.
11. A cushioning device for presses, said cushioning device embodying a relatively movable cylinder and piston, a source of supply of fluid under pressure for yieldingly resisting such relative movement, a passage leading to the other side of the piston, an exhaust, a spring controlled valve device for connecting said source of supply with said passage to maintain said cylinder and piston against such relative movement, a spring controlled valve device for connecting said passage with said exhaust, a rocker member for alternately actuating said valves, means operating automatically at predetermined times in the cycle of operation of the press for rocking said rocker member alternately in opposite directions, and means for assisting in rocking said member.
12. A cushioning device for presses, said cushioning device embodying a relatively movable cylinder and piston, a source of supply of fluid under pressure for yieldingly resisting such relative movement, a passage leading to the other side of the piston, an exhaust, a spring controlled valve device for connecting said source of supply with said passage to maintain said cylinder and piston against such relative movement, a spring controlled valve device for connecting said passage with said exhaust, a rocker member for alternately actuating said valves, means operating automatically at predetermined times in the cycle of operation of the press for rocking said rocker member alternately in opposite directions, and means for assisting in rocking said member, the last said means also operating to retain said rocker member in its rocked position.
13. A cushioning device for presses, said cushioning device embodying a relatively movable cylinder and piston, a source of

supply of fluid under pressure for yielding-
ly resisting such relative movement, a pas-
sage leading to the other side of the piston,
an exhaust, a spring controlled valve device
for connecting said source of supply with said
5 passage to maintain said cylinder and pis-
ton against such relative movement, a spring
controlled valve device for connecting said
passage with said exhaust, a rocker member
for alternately actuating said valves, means
10 operating automatically at predetermined
times in the cycle of operation of the press
for rocking said rocker member alternately
in opposite directions, and resiliently yield-
ing means operable upon said rocker member
15 for assisting in rocking the same, the last
said means also operating to yieldingly hold
said rocker member in its rocked position.

14. A cushioning device for presses, said
20 cushioning device embodying a cylinder and
piston element relatively movable, a source
of supply for supplying fluid under pressure
to said cushion to yieldingly resist said rel-
ative movement, a valve casing, a passage
25 leading from said casing to said source of
supply, a passage leading from said casing
to the opposite side of the piston, an exhaust
passage leading from said casing, a valve
in said casing for establishing and closing a
30 connection between said source of supply
and the first said passage whereby fluid un-
der pressure will be admitted to said other
side of the piston to prevent such relative
movement of the cylinder and piston ele-
35 ments, a valve in said casing for establish-
ing and closing communication between the
first said passage and said exhaust passage
to exhaust the fluid from said other side of
the piston, and means operable at a prede-
40 termined time in the cycle of operation of
the press for actuating said valves in timed
relation with respect to each other.

15. A cushioning device for presses, said
cushioning device embodying a cylinder and
45 piston element relatively movable, a source
of supply for supplying fluid under pres-
sure to said cushion to yieldingly resist said
relative movement, a valve casing, a passage
leading from said casing to said source of
50 supply, a passage leading from said casing
to the opposite side of the piston, an exhaust
passage leading from said casing, a valve in
said casing for establishing and closing a
connection between said source of supply
55 and the first said passage whereby fluid un-
der pressure will be admitted to said other
side of the piston to prevent such relative
movement of the cylinder and piston ele-
ments, a valve in said casing for establishing
60 and closing communication between the first
said passage and said exhaust passage to ex-
haust the fluid from said other side of the
piston, a rotating member, spaced active
portions on said member, and means for ro-
65 tating said member to cause said active por-

tions thereof to alternately actuate the said
valves.

In testimony whereof I have signed my
name to this specification, on this 1st day
of May, A. D. 1929.

FREDRICH J. RODE.
